ADJUSTABLE DRAWING BOARD

Onnie D. Stallings, Raleigh, N. C.

Application May 11, 1939, Serial No. 273,076

4 Claims. (Cl. 45—131)

The present invention relates to drawing boards and has for its primary object to provide an adjustable support for the rear edge of the board whereby to support the board in a desired inclined position for conveniently working thereon.

A further object of the present invention is to provide an adjustable support of this character which includes upper and lower frames hingedly connected at the front end and provided with a step by step adjusting structure at the rear end of the board and in which the upper frame is provided with attaching plates for attaching to the edge portion of the drawing board to secure the same in position on the frame so that neither the upper or lower surfaces of the drawing board are marred by the attaching elements in order that the working surface of the board may be reversed, when desired.

20 A further important object of the present invention is to provide an adjustable leg member for the rear of the board adapted to secure the rear edge thereof in a vertically adjusted position and also embodying fastening means for securing the board in its lowermost position and in which the supporting legs constitute a handle for conveniently carrying the board.

A still further object is to provide a device of this character of simple and practical construction, which is strong and durable, neat and attractive in appearance, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which—

40 Figure 1 is a rear elevational view showing the adjustable member at the rear of the board arranged in its uppermost position.

Figure 2 is a side elevational view.

Figure 3 is a rear elevational view showing the adjusting member in its lowermost position.

Figure 4 is a top plan view of the frame with the board removed therefrom.

Figure 5 is a sectional view through the base portion of the frame, taken substantially on a line 5—5 of Figure 4.

Figure 6 is a fragmentary side elevational view showing the board in an intermediate adjusted position.

Figure 7 is a fragmentary top plan view of the rear edge of the board showing the notches for

accommodating the paper clips to prevent interference by the T-square, and

Figure 8 is a fragmentary sectional view taken substantially on a line 8—8 of Figure 7.

Referring now to the drawings in detail, 5 wherein for the purpose of illustration I have disclosed a preferred embodiment of the invention, the numeral 5 designates a bottom frame member of substantially U-shaped form and including a pair of side members 6 connected at 10 their rear ends by a cross member 7 and the front-ends of the members 6 are hingedly connected at 8 to a pair of top frame members 9—9 arranged in overlying parallel relation with respect to the bottom side frame members 6. 15

To the rear end of the top frame members 9 is hingedly connected a leg member 10, the hinges being designated at 11. The leg member 10 is of substantially U-shaped form with its bight portion connected to the frame members 9 so that the leg portions 12 swing downwardly in a suspended position.

Secured to the upper surface of the cross member 7 adjacent each end thereof is a plurality of stepped blocks 13 upon the upper edges 25 of which the bottom edge of the respective leg members 12 are adapted to rest to adjust the rear edge of the frame in a vertically adjusted position.

Also secured to the cross member 7 are a 30 pair of upstanding headed members 14 adapted for engagement by a pair of spring catch members 15 carried by the leg portions 12 to releasably secure the legs in their lowermost position.

Secured to the front and rear ends of the upper 35 frame members 9 are angular plates 16 including an upstanding edge 17 adapted to engage the respective front and rear edges of a drawing board 18 for securing the board in position thereto by screws or the like 19.

The upper edge of each of the upper frame members 9 are provided with notches 20 to provide a space between the members 9 and the drawing board 18 to accommodate a T-square to be carried by the drawing board, when not 45 in use.

The rear edges of the drawing board are also provided with a plurality of notches 21 for accommodating the bight portion of U-shaped spring clips 22 adapted to secure the drawing 50 paper on the upper surface of the drawing board without necessitating the employment of thumbtacks.

As more clearly illustrated in Figure 5 of the drawings, the upper edge of the tallest block 13 55

is inclined inwardly to prevent accidental slipping of the leg members 12 therefrom.

When the leg member is secured in its lowermost position, as shown in Figure 3 of the drawings, the intermediate portion of the leg member constitutes a convenient hand grip by means of which the drawing board may be carried from place to place.

By reason of the fact that the drawing board 10 is secured in position to the upper frame at the edge portion of the board neither the upper or lower surface of the board is marred by the attaching screws or nails, and accordingly, should the upper surface of the board become marred 15 through usage the board may be reversed so as to provide a fresh unmarred working surface.

It is believed the details of constructions, advantages and manner of use of the device will be readily understood from the foregoing without 20 further detailed explanation.

Having thus described the invention, what I claim is—

1. In an adjustable drawing board, a lower frame member and an upper frame member 25 each of said frame members including a pair of spaced parallel side members hingedly connected at their front ends, a U-shaped supporting leg pivotally attached at its bight portion at the rear ends of the upper frame member, means 30 carried at the rear end of said lower frame member for supporting the free end portions of said leg member in a vertically adjusted position, and means for securing said supporting leg to the lower frame member in a position substantially 35 at right angles thereto for utilizing the bight portion of said supporting leg as a hand grip for carrying the board.

2. In an adjustable drawing board, a lower frame member and an upper frame member 40 hingedly connected at their front edges, a U-shaped supporting member pivotally attached at its bight portion to the rear edge of the upper

frame member the leg portions of said member extending freely downwardly, and means carried at the rear end of said lower frame member for engagement by the ends of the legs for supporting said upper frame member in a vertically adjusted position, and means for releasably securing the lower ends of the legs to the lower frame member, the bight portion of the supporting member being spaced from the upper frame member and constituting a hand grip for 10 carrying the board when the ends of the legs are in secured position.

3. In an adjustable drawing board, a lower frame member and an upper frame member 15 hingedly connected at their front edges, a U-shaped supporting member pivotally attached at its bight portion to the rear edge of the upper frame member, the leg portions of said member extending freely downwardly, stepped blocks rising from the rear end of said lower frame member 20 for selective engagement by the ends of the legs for supporting said upper frame member in a vertically adjusted position and means for releasably securing the lower ends of the legs to the lower frame member, the bight portion of 25 the supporting member being spaced from the upper frame member and constituting a hand-grip for carrying the board when the ends of the legs are in secured position.

4. A drawing board of the class described comprising a base, a board part, means for hinging the board part to one end of the base, a stepped member at the other end of the base, a second member hingedly connected to the adjacent end of the board and having its lower end adapted 30 to engage different steps for holding the board at different inclination and latch means for detachably connecting the second hinged member to the adjacent end of the base for holding the board part in lowered position with the second 35 hinged member engaging the lowermost step.

ONNIE D. STALLINGS.
